UNITED STATES PATENT OFFICE.

JOHN H. CRUSE, OF FELICITY, OHIO.

TILING.

SPECIFICATION forming part of Letters Patent No. 374,143, dated November 29, 1887.

Application filed February 23, 1887. Serial No. 228,637. (No model.)

To all whom it may concern:

Be it known that I, JOHN H. CRUSE, of Felicity, in the county of Claremont and State of Ohio, have invented a new and useful Improvement in Tiling, which improvement is fully set forth in the following specification and accompanying drawings, in which—

Figure 1 is a front perspective view of an arch with my improved tiling, and Fig. 2 is a front view of a modification.

My invention relates to an improvement in tiling; and it consists of a series of concave tiling-pieces beneath bridge-abutments, provided at the edges with dovetails or recesses 15 to receive keys therein, so as to secure them rigidly in position, and so disposed that the tiling will project beneath the side walls to further assist in retaining them in position and the walls from settling in quicksand bottoms, all of which will now be fully set forth in detail.

In the accompanying drawings, A represents vertical walls or arches, of any suitable style or material. B represents the tiling, which I design to so dispose as to have the edges project beneath the walls A a slight distance, the weight of the wall thus retaining them in position. These tiling are formed concave on their upper sides, or in the form of an ordinary arch reversed, with the side walls 30 or abutments resting on the outer ones, so as to retain them in position. The tiling B is provided with recesses C at opposite sides, so disposed that two of these recesses in opposite 35 sections of tiling will have a key, D, placed

therein, and thus prevent the said tiling from becoming detached. As will readily be noticed, this key D may be made of the same material as the ordinary tiling, and of any suitable color, and may be used as an ornament, 40 if desired, and for the purpose of retaining the tiling in position.

Fig. 2 represents a modification of my device, wherein the foot-courses of the side walls or arches are designed to project beyond the 45 main walls, so as to increase the bearing-surface of the walls.

As will readily be noticed, my device is especially designed to be used in places having quicksand or loam bottoms, where an ordinary 50 bridge-pier would readily settle.

Having described my invention, what I claim as new is—

1. A concave tiling provided with the oppositely-disposed recesses and joined together 55 with keys and extending under the edges of the walls, substantially as and for the purpose set forth.

2. The combination of the tiling having retaining-keys with the side walls resting on the 60 edges of the tiling, as and for the purposes set forth.

In testimony that I claim the foregoing I have hereunto set my hand, this 14th day of December, 1886, in the presence of witnesses.

JOHN H. CRUSE.
